UNITED STATES PATENT OFFICE

WILLIAM COSTELLO, JR., OF PHILADELPHIA, PENNSYLVANIA; ELIZABETH R. COSTELLO AND JOHN L. COSTELLO, ADMINISTRATORS OF SAID WILLIAM COSTELLO, JR., DECEASED, ASSIGNEES TO NATIONAL BISCUIT COMPANY, OF NEW YORK, N. Y., A CORPORATION OF NEW JERSEY

FEEDING MECHANISM

Application filed November 10, 1923. Serial No. 673,839.

This invention relates to improvements in feeding mechanisms, and relates more particularly to feeding mechanisms used in connection with the cake baking industry. It will be understood, however, that the mechanism may find useful application in other industries, and its use is by no means limited to the specific purpose hereinafter set forth.

After applying a coating or icing to cakes or crackers, it is customary to place the coated articles on trays for drying. In the present instance, I show the mechanism which forms the subject of the present invention applied to the feeding of cakes from the coating mechanism to the drying trays, and one of the principal objects of the present invention is to provide improved means whereby the cakes are accurately placed upon the trays and whereby they are prevented from being laid unduly near or over the edges of the trays.

The invention further resides in novel and advantageous features of construction and in a novel adjusting means which provides for the adjustment of the mechanism for cakes or other articles of different sizes.

In the attached drawings:

Figure 1, is a side elevation of a machine made in accordance with my invention;

Fig. 2, is a longitudinal section;

Fig. 3, is a transverse section on the line 3—3, Fig. 1;

Fig. 4, is a transverse section through the line 4—4, Fig. 1;

Fig. 5, is a fragmentary enlarged section showing the operating cam and the immediately associated parts;

Fig. 6, is a plan view of the parts shown in Fig. 5;

Fig. 7, is a fragmentary enlarged section illustrating details of the tray conveyer operating mechanism;

Fig. 8, is a section on the line 8—8, Fig. 7;

Fig. 9, is a side elevation of one end of the machine illustrating a modification within the scope of the invention;

Fig. 10, is a fragmentary section illustrating the operating cam of the modification illustrated in Fig. 9 together with the associated adjustable parts, and

Fig. 11, is a plan view of the parts of the mechanism illustrated in Fig. 10.

With reference to the drawings, the machine comprises a main frame consisting of two side pieces, 1, 1, connected by tie rods 2, 2. Journaled in the side pieces 1, 1, near the bottom is a transverse shaft 3 which, as shown in Fig. 3, extends at one side beyond the side piece and is thereby adapted for connection with an external source of power, not shown.

The shaft 3 carries at one end a sprocket 4 which is connected by a chain 5, see Figures 1 and 3, with a sprocket 6 upon a shaft 7 journaled at the top of the main frame in the side pieces 1, 1. This shaft 7 carries intermediate the side frames a roller 8 around which passes an endless belt conveyer 9. The conveyer 9 extends from the top of the roller 8 horizontally across the top of the frame, it being supported in this horizontal stretch on lateral rods 11 extending between two bars 12, 12, mounted respectively at the tops of the side pieces 1. After passing over the last of the supporting rods 11, the conveyer belt inclines downwardly and passes around a roller 13 whose ends are journaled in side flanges 14, 14, of a plate 15 having trunnions 15^a journaled in a pair of blocks 16, 16, which latter are slidably mounted in suitable guides 17, 17, at the tops of the respective side pieces 1, 1. The guides 17 each also carries a threaded shaft 18 which extends through the block 16, and has at one end a hand wheel 19 by means of which the shaft may be rotated to adjust the blocks 16 longitudinally in their guides. Further adjustment of the roller 13 may be had by means of a lever 21 respectively attached to one of the trunnions 15^a and constituting means for rotating the said plate 15 upon its pivots. The handle 21 is also provided with a threaded bolt 22 the lower end of which is adapted to bear against the top of one of the side pieces 1, whereby the lever 21 may be adjusted to different positions. A lock nut 23 prevents unintentional turning of the screw 22 in the lever 21.

After passing around the roller 13, the conveyer 9 returns to the under side of the roller 8 and around the roller, the belt intermediate the roller 13 and the roller 8 passing over the

edge of a plate 24 secured to the side frames 1, 1, and constituting a scraper which keeps the outer surface of the conveyer 9 clean. It will be apparent that the above-described arrangement relative to the roller 13 permits lateral adjustment of the rod to give the belt 9 the desired tension, and permits also a limited vertical movement of the rod for a purpose to be described hereinafter.

With further reference to Figures 2 and 3, it will be noted that the shaft 3 carries a second sprocket 25, which is connected by a chain 26 to a sprocket 27 loosely mounted, as shown in Fig. 8, upon a shaft 28 journaled in bearings 29, 29, on a sub-frame constituted by a pair of beams 31, 31, and tie rods 32 connecting said beams. The sub-frame is mounted in the main frame upon rollers 33, 33, two of which are located at each side of the main frame supported on studs 34 which pass through the side pieces 1, 1, as best shown in Fig. 3. As will be apparent, each of the rollers 33 is provided with a pair of spaced peripheral flanges 35, 35, between which the beams 31, 31, which in the present case are of U-section, are confined. The rollers 31 at one end of the machine are slightly higher in the present instance than the others, and a spring 36 shown in Fig. 1 is provided one end of which is secured to one of the tie rods 32 and the other end to a rod 37 which passes through a sleeve 38 pivotally supported on one of the main frame cross bars 2, as clearly illustrated in Fig. 1. The extremity of the rod 37 is threaded and is provided with a suitable nut 39 in the form of a hand wheel which provides for the adjustment of the rod in its sleeve 38 to regulate the tension of the spring 36 which tends to hold the sub-frame 31-32 in an advanced position. The advanced position of the frame 31-32 is limited by an arm 41 on a tie rod 2 extending between arms 42, 42, on the side pieces 1, 1, the arm 41 being adjustable on the rod 2 by reason of a set screw 43 which normally secures the arm to the rod. In limiting the forward movement of the said frame 31-32, a roller 44 in the end of the arm 41 is adapted to engage a cam 45 on the shaft 28, as best shown in Figs. 5 and 6. The aforescribed arrangement is such that as the shaft 28 rotates and with it the cam 45, the sub-frame 31-32 is shifted on its rollers against the tension of the spring 36, and back as the roller 44 and the cam assume the relative positions shown in broken lines in Fig. 5, the upward movement of the frame 31-32 being abrupt by reason of the contour of the cam.

As previously set forth, the power shaft 3 is connected through the sprocket 25 and chain 26 with a sprocket 27 loosely mounted upon the shaft 28. As shown in Fig. 8, the sprocket 27 is confined between a collar 47 fixed to the shaft and a second collar 48 also fixed to the shaft and comprising ratchet

teeth 49. The sprocket 27, as best shown in Fig. 7, carries a pawl 51 which by means of a spring 52 is made to bear against the ratchet 49 on the collar 48. In normal rotation of the sprocket 27 by the shaft 3, the pawl 51 and ratchet 49 constitute a locking means which transmits the rotation of the sprocket 27 to the shaft 28. The arrangement, however, is such as to permit rotation of the shaft 28, for a purpose to be described hereinafter, in its normal direction independent of the sprocket 27 and the associated parts of the transmission.

As shown in Figs. 1 and 2, the shaft 28 carries two sprockets 54, 54, one at each side of the sub-frame 31-32, and these sprockets are respectively connected by means of a pair of conveyer chains 55, 55, with a pair of sprockets 56, 56, on a shaft 57 on the upper end of the sub-frame 31-32, the shaft 57 being carried in journal-boxes 58, 58, adjustable longitudinally of the sub-frame in guides 59, 59, there being provided at the inner end of said guides, bolts 61, 61, in threaded engagement with the frame or that part of the frame which constitutes the guides 59, said bolts bearing against the journal-boxes 58, and constituting means for adjusting the tension of the conveyer chains 55, 55.

Supported on brackets 63, 63, secured to the beams 31, as shown in Fig. 4, is a platform 64 having longitudinal slits 65, 65, through which the upper runs of the chains 55 travel. Each of the chains also carries at intervals lugs 66 which project upwardly through the slits above the top of the platform 64 and form means for advancing over said platform trays 67 which, as shown in Fig. 2, are of such width as to occupy substantially all the space between the successive lugs 66 on the said chains. As shown in Fig. 4, in which one of the trays 67 is shown in broken lines, the trays each comprise side pieces 68, 68, of such height as to permit the stacking of the trays upon each other without injury to the cakes or other articles on the tray. On these trays, which are adapted for stacking, the cakes are permitted to dry.

As shown in Fig. 1, there is supported at the lower end of the sub-frame 31-32 on uprights 71, 71, secured to one of the beams 31, a backstop 72 which as shown in Figs. 1 and 3 lies at one edge of the platform 64 opposite the point at which the trays 67 may be slid in upon the upper run of the conveyer chains 55, 55, the stop 72 insuring proper positioning of the trays laterally of the conveyer.

The operation of the above described mechanism is as follows: The cakes or other articles are fed to the conveyer 9 in any desired manner, but preferably in evenly spaced rows extending the entire width of the conveyer. In the present instance, I have illustrated cakes so deposited upon the said con-

veyer 9 in transverse evenly spaced rows, the depositing mechanism being indicated in Fig. 2 as 74. The cakes are advanced on the conveyer 9 towards the outer end of the latter, which passes around the roller 13 as before described, and this roller is so adjusted vertically as to lie close to the top of the trays 67 as they advance on the conveyer 55. The cakes as they reach the end of the conveyer 9 and as shown in Fig. 2 pass off the latter conveyer upon the trays 67, which are advancing upon the conveyer chains 55, 55.

In order to preclude the possibility of a row of cakes being deposited immediately over the juncture of adjoining trays, I have provided the mechanism constituted by the cam 45 and the arm 41, the operation of which was previously described and provides for the sharp bodily movement of the sub-frame 31-32 with the conveyer 55 and the trays carried by the conveyer when the trays have reached the position shown in Fig. 2. The extent of this forward movement of the sub-frame 31-32 is controlled or may be adjusted by means of a limit stop comprising a pair of lugs 75, 75, secured to the respective beams 31, 31, and a corresponding pair of adjustable bolts 76 suitably threaded in the side frames 1, 1, and adapted to engage the said lugs 75 when the sub-frame advances under the action of the spring 36 when released by the cam 45. By adjustment of the bolts 76, the extent of the forward movement may be controlled. This forward movement of the sub-frame 31-32 carries the whole mechanism of the conveyer 55, 55, forward to an extent eliminating the possibility of a row of cakes being deposited at the juncture of the frames. The return movement of the sub-frame is in the present instance gradual by reason of the cam contour.

For proper operation of this device, it is essential that the initial row of cakes be deposited at the proper point upon the initial tray, and in order to insure this, the shaft 57 is provided with a hand wheel 77, see Fig. 1, whereby the conveyer chains 55, 55, may be advanced by hand. This manual advancement of the conveyer chains 55, 55, is permitted by the device illustrated in Figs. 7 and 8, which permits the movement of the sprocket 27 independent of the shaft 28. In making this adjustment, the mechanism is set in operation until the initial row of cakes or other articles is about to leave the conveyer 9, after which the mechanism is stopped and the hand wheel 77 operated to bring the moving tray into a position such that it will receive at the proper point the initial row of the articles.

The roller 44 acts as an abutment against which the cam 45 bears during its rotation to move the sub-frame 31-32 and the conveyer 55 rearwardly at a definite speed, and when the point of said cam passes said roller the

spring 36 moves said sub-frame and said conveyer forward at an increased rate of speed. The forward movement of the conveyer and the sub-frame is controlled by the screw 76 against which the stop 75 strikes. By turning the screw 76, the said accelerated forward movement may be varied in accordance with the size of the articles being deposited on the said conveyer, the smaller articles requiring a shorter accelerated travel of the conveyer than those of larger proportions. When the accelerated forward movement of the conveyer is short, the cam 45 does not bear against the roller stop 44 throughout its entire revolution. It is, therefore, obvious that the stops 44 and 75 both function to control the forward movement of the sub-frame at different stages of said movement under the conditions above noted.

In Figs. 9, 10 and 11, I have illustrated a modification within the scope of the invention, the modification concerning chiefly the adjustment for limiting the forward movement of the sub-frame 31-32. In this instance, the cam 45 engages a roller 78 upon an arm 79 pivotally mounted on a pin 81, which latter is held in a bracket 82 secured to a cross bar 83 on the main frame. The arm 79 has fixed thereto an arcuate rack 84 which meshes with a pinion 85 on a shaft 86 journaled in the side pieces 1, 1. The shaft carries at its outer end a worm wheel 87 which meshes with a worm 88 on a vertical spindle 89 journaled at 91 in one of the side frames 1, said spindle having at the top a hand wheel 92 by means of which it may be rotated. By manipulation of the hand wheel 92, the arm 79 may be adjusted around its center to various positions, thereby altering the position of the roller 78 with respect to the shaft 28 and varying the throw of the cam and the consequent movement of the sub-frame 31-32. The movement of the arm 79 around its pivot 81 is limited by providing in the arm an arcuate slot 93 through which extends the shaft 86, as illustrated in Fig. 10.

I claim:

1. In combination, a conveyer, a second conveyer adapted to receive articles from the first conveyer, mechanism for normally actuating the conveyers and for giving the said second conveyer an intermittent bodily movement of reciprocation in directions substantially parallel to its normal advance movement, the movements of said reciprocation being effected at speeds relatively different one from the other.

2. The combination with a conveyer, of a second conveyer movable under the first and adapted to receive articles therefrom, mechanism common to both conveyers for normally operating the conveyers, and mechanism for periodically and bodily reciprocating the second conveyer relative to the first conveyer in directions parallel to its normal

- advance movement for accelerating the normal forward movement of the second conveyer, the movements of reciprocation being effected at relatively different speeds one to the other. 5
3. The combination with a main frame, of a conveyer mounted in said main frame, a sub-frame movably supported on the main frame, a conveyer carried by the sub-frame and adapted to receive articles from the said first conveyer, mechanism for operating on their respective frames the said conveyers, and mechanism for reciprocating the sub-frame on the main frame in directions substantially paralleling the normal advance movement of said second conveyer, each movement of said reciprocation being effected at a speed relatively different from the other movement thereof. 10
4. The combination with a main frame, of a conveyer mounted in the main frame, a sub-frame movably mounted on the main frame, a conveyer carried by the sub-frame, mechanism for actuating on their respective frames the said conveyers, and mechanism including a cam for reciprocating the sub-frame on the main frame in directions paralleling the normal advance movement of the said second conveyer, each movement of said reciprocation being effected at a speed relatively different from the speed of the other movement thereof. 15
5. The combination with a main frame, of a conveyer mounted on the main frame, a sub-frame movably mounted on the main frame, a conveyer carried by the sub-frame and adapted to receive articles from the said first conveyer, mechanism for actuating on their respective frames the said conveyers, mechanism for reciprocating the sub-frame in the main frame in directions substantially paralleling the normal advance movement of said second conveyer, and an adjustable stop for limiting the extent of reciprocation of the sub-frame. 20
6. The combination with a main frame, of a conveyer mounted on the main frame, a sub-frame movably mounted on the main frame, a conveyer carried by the sub-frame and adapted to receive articles from the said first conveyer, mechanism for actuating on their respective frames the said conveyers, a shaft carried by the sub-frame, a cam mounted on the shaft for moving the sub-frame in one direction, a spring for moving the sub-frame in the opposite direction, an adjustable arm on the main frame adapted to be engaged by the cam, and means for rotating the cam shaft whereby the sub-frame is reciprocated in the main frame in directions substantially paralleling the normal advance movement of said second conveyer. 25
7. The combination with a pair of relatively movable frames of a conveyer mounted on each of said frames and fixed against bodily movement with respect thereto, one of said 30
- conveyers being adapted to receive articles from the other, mechanism for operating the conveyers on their respective frames, and mechanism for effecting a relative reciprocation of the frames in directions longitudinally of said conveyers, the movements of said reciprocation being effected at speeds relatively different one from the other. 70
8. The combination with a pair of relatively movable conveyers, one of which is adapted to receive articles from the other, of mechanism for actuating the conveyers, and mechanism for reciprocating one of the conveyers longitudinally and with respect to the other, said reciprocating mechanism including 75 means for making that part of the reciprocation which is in the direction of the normal movement of the conveyer comparatively fast with respect to the return movement. 80
